REMOVABLE TOP STOP

Davis Marinsky, Bronx, N. Y.; Louis H. Morin
executor of said Davis Marinsky, deceased, as-
signor of one-half to said Louis H. Morin

Application May 2, 1945, Serial No. 591,514

20 Claims. (Cl. 24—205.11)

1

This invention relates to separable fastener stringers. More particularly, the invention deals with a removable top stop comprising a yoke like member adapted for attachment to a predetermined number of end scoops at one end of a stringer in forming substantially within the boundaries of the scoops a means blocking end scoops from coupling engagement, thus checking movement of a conventional slider in the direction of said end of the stringers. Still more particularly, the invention includes a top stop device having means thereon preventing displacement of a slider from a single stringer as and when the stringers are completely separated. The novel features of the invention will be best understood from the following description when taken together with the accompanying drawing, in which certain embodiments of the invention are disclosed, and in which the separate parts are designated by suitable reference characters in each of the views, and in which:

Fig. 1 is a side view of one end portion of the stringer of a separable fastener illustrating a top stop mounted on end scoops of the stringer.

Fig. 2 is a front edge view of the structure as seen in Fig. 1.

Fig. 3 is a section on the line 3—3 of Fig. 1, diagrammatically illustrating the manner of attaching the yoke to end scoops in forming the top stop.

Fig. 4 is a perspective view of a top stop yoke, detached.

Fig. 5 is a view similar to Fig. 4, showing a modified form of device; and

Fig. 6 is a view similar to Figs. 4 and 5, showing another modification.

In separable fasteners of the class defined, there are times when it is desirable to remove top stops from the stringers. In most instances, these tops have been directly applied to the stringer tapes, and removal of the stops results in damage to the tape.

It is the purpose of my invention to provide a top stop which is directly applied to the coupling end portions of two or more scoops and is in the form of a simple yoke shaped body which can be easily applied to the scoops and also easily removed therefrom. Attachment and detachment of the stop to the scoops in no way will mar or injure the tape. Furthermore, I provide a top stop device which is substantially contained within the boundaries of side surfaces of the scoops so that the stop can enter the channels of the conventional slider and thereby permit movement of the slider to the extreme end of the

stringers. On the other hand, the degree of this movement can be determined by the location or arrangement of the top stop on the scoops or by the number of scoops engaged thereby.

In illustrating one adaptation and use of the invention, I have shown in Figs. 1 and 2 at 10 a part of a stringer tape upon the beaded edge 11 of which is secured, at longitudinally spaced intervals, a plurality of scoops 12. The scoops are generally of the coreless V-shaped cross sectional form, illustrated in the application of Louis H. Morin on "Scoops for separable fastener stringers" Ser. No. 531,618 filed April 18, 1944, being modified solely by employing wing like male coupling end portions 13 which converge in the direction of the ends 14 and 15 thereof instead of having substantially parallel walls, as illustrated in the application in question. The recessed or female coupling portions 16 of the scoops 20 are recessed at their sides, as seen at 17 and 18, note Fig. 3. The ends 14 and 15 are, however, substantially in alignment with the side surfaces 19 and 20 of the mounting end portion 21 of the scoops.

25 My invention is not particularly concerned with the specific structure of the scoops except insofar as their adaptation for use in connection with my improved top stop yokes, one of which is shown at 22, note Figs. 1, 2 and 4 of the drawing. The yoke 22 may also be defined as an elongated ring, and comprises upper and lower members 23 and 24 joined by side members 25 and 26.

In originally forming the top stop yoke 22, the upper and lower members 23 and 24 are bent 35 centrally to a slight extent, thus disposing the sides 25 and 26 angularly to each other, and this normal position of the top stop blank is indicated in dotted lines in Fig. 3 of the drawing. In this position, the opening between the side wall members 25 and 26 is sufficient to provide free passage 40 of the top stop over the ends 14 and 15 of the scoops.

In Fig. 3 of the drawing I have diagrammatically illustrated a manner of attaching the top stop 22 to end scoops 12 of a stringer, which consists in moving two tools or jaw members 29 and 30 into engagement with the side members 25 and 26 of the top stop, and then toward each other to move the members 25 and 26 into the recesses 17 and 18 by increasing the bend, as at 50 27. The members 25 and 26 entering the recesses 17 and 18 will permanently retain the top stop 22 against displacement from the three scoops arranged within the now smaller opening 28, 55 as will clearly appear from a consideration of

Figs. 1 and 3 of the drawing. The side members 25 and 26 are disposed within the side boundaries of the scoops, thus permitting the scoops to enter the channels of the conventional sliders, which are well known in this art. The stops 22 form blocking elements preventing the coupling of scoops of opposed stringers and this blocking will take place within the bounds of the slider, at least with respect to the innermost scoops arranged within the top stop yoke or element.

In Fig. 5 of the drawing is shown a slight modification wherein the top stop 31 comprises what might be termed a multiple yoke. In other words, the side members 32 and 33 instead of being joined just by top and bottom members 34 and 35 are also joined by two intervening members 36 which form three openings 37 instead of the one large opening 28. The top stop 31 is adapted specifically for mounting on three scoops, and the three scoops will be free to pass through the openings 37, the members 36 being disposed between adjacent scoops, as will be apparent. Aside from this change in construction, the top stop 31 will be the same as that shown in Figs. 1 to 4 inclusive and arranged in position the same as taught in Fig. 3.

In Fig. 6 of the drawing is shown another top stop 38 which differs from the stop 31 primarily in adding to the side members 39 and 40 thereof extending wings or supplemental stop members 41 and 42, the purpose of which is to extend beyond the side surfaces of the scoops to engage the slider, preventing displacement of the slider from the end of the stringer. This type of construction is adaptable for use in what is termed separable stringers. For example, stringers as applied to lumberjackets and similar uses where the two stringers are completely separated from each other. In such instances, the slider is retained always upon one of the stringers and the top stop of this stringer will include the outwardly extending top wings 41 and 42 to retain the slider against displacement. As previously stated, the boundaries of the side members of the top stop are disposed within the recesses, or in other words, within the side surfaces of the scoops, enabling the stop to enter the slider.

The end stop 38 of Fig. 6 has the two cross members 43, similar to the members 36 and the three recesses 44 similar to the recesses 37.

In top stops of the kind defined, these stops can be removed by reversely bending the stop to the end of spreading the side members thereof sufficiently to clear the coupling end portions of the scoops. By employing pliable metal in the top stops, a detached or removed top stop can be re-installed into operative position and hand tools, such as a pair of pliers, can be utilized to accomplish this result. Where suitable tools are not available, any one of the walls of the top stop can be cut or ruptured sufficiently to remove the top stop, and then a new top stop can be re-applied. This type of construction will lend itself to making of repairs by a dealer or distributor or even by the purchaser. By reason of the simplicity of the device, desired repair can be quickly and easily accomplished. It will be apparent that all attachments as well as detachments of the top stops is accomplished without in any way injuring or marring the mounting tape of the fastener, in that the top stop is disposed on the coupling portions only of the scoops and beyond the limits of the tape edge. It will also be understood that the stop yoke or element is also applicable to the stringer at any point along the string-

ers where it would be desirable to check movement of a slider thereon. This is also particularly true in double action stringers upon which dual sliders can be operated and movement of the sliders checked at predetermined points intermediate the stringer ends.

It will be apparent that the recessed surfaces of the coupling end portions of the scoops may be said to form on these coupling end portions reduced necks for the reception of the top stop member or yoke.

The yoke considered as an article of manufacture may be said to comprise a body defined by side and end bars, resulting in the yoke shaped contour of the body. Also, the side bars may be joined by supplemental or intermediate bars which would result in forming a yoke having several recesses or openings.

Having fully described my invention, what I claim as new and desire to secure by Letters Patent is:

1. A top stop for the stringer of separable fasteners, said stringer comprising a tape having scoops spaced longitudinally of one edge portion thereof, said scoops having coupling ends beyond the tape edge, said coupling ends having reduced neck portions, and said stop comprising a yoke fitting on the neck portions of a predetermined number of end scoops of said stringer.

2. A top stop for the stringer of separable fasteners, said stringer comprising a tape having scoops spaced longitudinally of one edge portion thereof, said scoops having coupling ends beyond the tape edge, said coupling ends having reduced neck portions, said stop comprising a yoke fitting on the neck portions of a predetermined number of end scoops of said stringer, and said yoke being substantially V-shaped in cross sectional form.

3. A top stop for the stringer of separable fasteners, said stringer comprising a tape having scoops spaced longitudinally of one edge portion thereof, said scoops having coupling ends beyond the tape edge, said coupling ends having reduced neck portions, said stop comprising a yoke fitting on the neck portions of a predetermined number of end scoops of said stringer, said yoke being substantially V-shaped in cross sectional form, and said yoke including transverse parts arranged between adjacent scoops disposed within said yoke.

4. A top stop for the stringer of separable fasteners, said stringer comprising a tape having scoops spaced longitudinally of one edge portion thereof, said scoops having coupling ends beyond the tape edge, said coupling ends having reduced neck portions, said stop comprising a yoke fitting on the neck portions of a predetermined number of end scoops of said stringer, said yoke being substantially V-shaped in cross sectional form, said yoke including transverse parts arranged between adjacent scoops disposed within said yoke, and said yoke having laterally projecting members at the outer end thereof extending beyond the side limits of the scoops of said stringer.

5. The combination with the coupling end portions of the scoops of a separable fastener stringer, of a stop element comprising a member enveloping the coupling end portion of a predetermined number of scoops, and means on said member and scoops preventing accidental displacement of the member from the coupling end portions of said scoops.

6. The combination with the coupling end portions of the scoops of a separable fastener stringer,

of a stop element comprising a member enveloping the coupling end portion of a predetermined number of scoops, means on said member and scoops preventing accidental displacement of the member from the coupling end portions of said scoops, and said member being arranged within side boundaries of the scoops of said stringer.

7. The combination with the coupling end portions of the scoops of a separable fastener stringer, of a stop element comprising a member enveloping the coupling end portion of a predetermined number of scoops, means on said member and scoops preventing accidental displacement of the member from the coupling end portions of said scoops, said member for the most part being arranged within the side boundaries of said scoops, and one end of said member having laterally projecting parts extending beyond the side limits of the scoops.

8. The combination with the coupling end portions of the scoops of a separable fastener stringer, of a stop element comprising a member enveloping the coupling end portion of a predetermined number of scoops, means on said member and scoops preventing accidental displacement of the member from the coupling end portions of said scoops, said member for the most part being arranged within the side boundaries of said scoops, one end of said member having laterally projecting parts extending beyond the side limits of the scoops, and said member including parts arranged between adjacent scoops engaged thereby.

9. The combination with scoops having recessed side portions in the coupling ends of the scoops, of a stop or blocking member enveloping a predetermined number of scoops and arranged within said recessed sides of the scoops.

10. The combination with scoops having recessed side portions in the coupling ends of the scoops, of a stop or blocking member enveloping a predetermined number of scoops and arranged within said recessed sides of the scoops, and said member including parts arranged between adjacent scoops disposed within said member.

11. The combination with scoops having recessed side portions in the coupling ends of the scoops, of a stop or blocking member enveloping a predetermined number of scoops and arranged within said recessed sides of the scoops, said member including parts arranged between adjacent scoops disposed within said member, and one end of the member having a projecting flange extending beyond one side surface of the scoops.

12. A stop or blocking element for scoops of separable fastener stringers of the kind defined, said element comprising a body defined by integral side and end bars, and said end bars being substantially V-shaped in form.

13. A stop or blocking element for scoops of separable fastener stringers of the kind defined, said element comprising a body defined by integral side and end bars, said end bars being substantially V-shaped in form, and other V-shaped bars joining the side bars intermediate said end bars.

14. A stop or blocking element for scoops of separable fastener stringers of the kind defined, said element comprising a body defined by integral side and end bars, said end bars being substantially V-shaped in form, other V-shaped bars joining the side bars intermediate said end bars, and the side bars having outwardly projecting parts at one end thereof.

15. The combination with a fastener tape hav-

ing spaced scoops thereon, each scoop having a mounting end portion and, beyond the tape edge, a reduced neck portion and an enlarged head, of a yoke member having end bars spaced to enter between pairs of scoops and side bars normally spaced for passage over the enlarged heads of the scoops, said end bars being deformed to introduce the side bars into the recesses formed by the neck portions of the scoops.

16. In a separable fastener stringer comprising a fastener tape having spaced scoops thereon and wherein said scoops are provided with mounting end portions for gripping the edge of the tape and coupling end portions having enlarged heads and reduced neck portions, the improvement comprising a stop embracing a predetermined number of end scoops of said stringer, said stop extending in the reduced neck portions of said scoops longitudinally with respect to the tape edge and also extending between the heads of the end scoops embraced therein transversely with respect to said tape edge.

17. In a separable fastener stringer comprising a fastener tape having spaced scoops thereon and wherein said scoops are provided with mounting end portions for gripping the edge of the tape and male and female coupling end portions, said female coupling end portions having side recesses, the improvement comprising a stop embracing a predetermined number of end scoops of said stringer, said stop extending in the side recesses of the female coupling end portions of said scoops longitudinally with respect to the tape edge and extending between the male coupling end portions of said scoops transversely with respect to the tape edge.

18. In a separable fastener stringer comprising a fastener tape having spaced scoops thereon and wherein said scoops are provided with mounting end portions for gripping the edge of the tape and male and female coupling end portions, said female coupling end portions having side recesses, the improvement comprising a stop embracing a predetermined number of end scoops of said stringer, said stop extending in the side recesses of the female coupling end portions of said scoops longitudinally with respect to the tape edge and extending between the male coupling end portions of said scoops transversely with respect to the tape edge, said stop having projecting members at its outer end extending beyond the side limits of said scoops.

19. In a separable fastener stringer comprising a fastener tape having spaced scoops thereon and wherein said scoops are provided with mounting end portions for gripping the edge of the tape and male and female coupling end portions, said female coupling end portions having side recesses, the improvement comprising a stop embracing a predetermined number of end scoops of said stringer, said stop extending in the side recesses of the female coupling end portions of said scoops longitudinally with respect to the tape edge and extending between the male coupling end portions of said scoops transversely with respect to the tape edge, said stop being arranged in substantial alignment with the side surfaces of the mounting end portions of the scoops.

20. In a separable fastener stringer comprising a fastener tape having spaced scoops thereon and wherein said scoops are provided with mounting end portions for gripping the edge of the tape and coupling end portions having enlarged heads and reduced neck portions, the improvement comprising a stop embracing a predetermined num-

ber of end scoops of said stringer, said stop extending in the reduced neck portions of said scoops longitudinally with respect to the tape edge and interlocked against removal from the scoops, endwise of the latter, by the said enlarged heads.
